PENCIL

J. D. Buchanan, Burbank, Calif.

Application June 2, 1944, Serial No. 538,444

7 Claims. (Cl. 120—17)

The invention relates to a pencil, and particularly to a so-called automatic lead pencil wherein the user can advance the lead from time to time to replace the point as it wears away.

An object of the invention is to provide a lead pencil of the automatic type wherein the lead may be advanced from time to time by the operator, and wherein neither the lead itself nor any operating member on the exterior of the pencil are employed to advance the lead. This object is accomplished by housing the lead advancing mechanism inside of the pencil case and operating the same under control of a weight, also housed in the pencil case, the weight being operable by bodily movement of the pencil. For example, the weight can be moved, when the pencil is grasped as usual for writing and given a sudden throw to operate the feeding mechanism and advance the lead. In making this sudden throw, the pencil is grasped in the manner normal when employing it for writing purposes and by a wrist movement, the pencil is quickly moved along its longitudinal axis in the direction of the point of the pencil and this movement is suddenly checked at the bottom of this throw or movement. An important feature of the invention is to feed the lead through the pencil without changing the writing grasp on the pencil.

For further details of the invention, reference may be made to the drawings wherein;

Fig. 1 is a longitudinal sectional view of a pencil according to the present invention, showing the weight retracted.

Fig. 2 is a longitudinal sectional view of the pencil of Fig. 1 with the weight in advanced position.

Fig. 3 is an enlarged longitudinal sectional view with parts broken away of the pencil of Figs. 1 and 2 and with the parts in the position shown in Fig. 2.

Fig. 4 is a view in cross-section on line 4—4 of Fig. 3.

Figs. 5 and 6 are longitudinal sectional views of a modified form of the invention, these two views showing the operating parts in different positions.

Fig. 7 is an enlarged longitudinal sectional view of the pencil of Figs. 5 and 6, with parts broken away, showing the parts in the same position as in Fig. 6.

Fig. 8 is a cross-sectional view on line 8—8 of Fig. 7.

Figs. 9 and 10 are longitudinal sectional views of a further modification of the invention, these

two figures showing the operating parts in different positions.

Fig. 11 is a longitudinal sectional view of the pencil of Figs. 9 and 10, with parts broken away and showing the parts in the same position as in Fig. 9.

Fig. 12 is a cross-sectional view on line 12—12 of Fig. 11.

Fig. 13 is a longitudinal sectional view of the preferred form of the invention.

Referring in detail to the drawings, one form of the invention shown in Figs. 1 to 4, inclusive, comprises a pencil 1, having a hollow case 2, the front end of which is provided with internal screw threads 3, receiving the external screw threads 4 on a tip or plug 5 which is tapered, shown at 6, to stimulate the sharpened end of a lead pencil. An elongated piece of lead 7 having aligned sections or pieces such as 35, 36, 20 slidingly fits in a bore 8 at the tip of the plug 5 and in a well-known spring friction bearing 9 and in the bore of a bearing 10 in the plug 5. At an intermediate place on the case 2, the lead 7 is guided by a central aperture 11 in a bearing or guide block 12 fixed at the upper end of the circular bore 13. This bore 13 extends in the same diameter from the bearing 12 to the top 14 of the plug 5 and its bearing 10. At the rear of the guide block 12 the bore of the case 2 may be of reduced diameter as indicated at 15, the bore 15 at its rear end having a guide block 16 fixed in an enlarged bore 17 at the rear end of the pencil 1 to receive an eraser not shown. The guide block 16 has a central aperture 18 which, like aperture 11, is slightly larger than the lead 7.

The guide blocks 12 and 16 may have tapered bores on the rear faces thereof indicated at 18 and 20, respectively, to guide the lead 7 centrally of the case 2 when the lead 7 is fed into the case 2 from the rear end 21 thereof.

The lead 7 is shown as comprising a plurality of sections or pieces such as 35 and 36, each of which is shorter than the bore 15 which serves as a storage chamber for a plurality of lead sections such as 35, 36, which may be fed into the bore 15 one at a time through the guide block 16. The lead sections such as 35 and 36 find their way one at a time out of the bore 15, through the guide block 12 and they line up as indicated in the bore 25 of the tube 24.

That part of the case 2 which is provided with the bore 13, forms a housing in which slidingly fits an elongated hollow weight 22 which may be of brass. The length of the weight 22 is shorter

than the length of that portion of recess 13 in which it slides, so that the weight 22 can move with respect to the case 2 when the latter is given a quick downward throw or thrust by a movement of the wrist, to effect feed of the lead 7.

The weight 22 has a central bore 23 in which slidingly fits a tube 24 which at the major portion of its upper end has a central bore 25 slightly larger than the lead 7. The tube 24 at its forward end carries a circular array of spring clutch members 26 which when forced against the lead 7 as shown in Fig. 1, grasp the lead 7 and feed it forward under the impact of the weight 22 which overpowers compression spring 31. The clutch 26 is held in engagement with lead 7 at certain times, and at other times is permitted to open and release the lead 7, by a clutch operated member 27 which is in the form of a hollow shell having at its upper end a bore 28 in which slidingly fits the forward end of the tube 24. The clutch operating member 27 at its forward end is provided with an inwardly projecting ring portion 29 which cooperates with and rides on the exterior taper 30 at the forward end of the clutch 26. The taper 30 tapers away from the axis of the case 2 in a rearward direction, so that the clutch 26 is forced against and locked to the lead 7 when the ring 29 rides up on the taper 30 as shown in Figure 1, whereas the clutch 26 opens and is released when ring 29 moves forwardly with respect to taper 30 as shown in Fig. 2.

Around the clutch operating member 27 is arranged a compression spring 31 which bears at its upper end against a shoulder 32 on the clutch shell 27. Spring 31 at its lower end bears against the top 14 of the plug 5.

When the pencil 1 is grasped in the hand in the same manner as if the pencil were to be employed for writing purposes, if a wrist movement gives the pencil a downward bodily thrust or movement which is suddenly arrested, the downward movement of the case 2 stops when the wrist movement stops, but the momentum of the weight 23 carries this weight forward, whereupon its front end 33 strikes the rear end 34 of the clutch operating member 27, the clutch 26 remaining locked to the lead 7 and carrying or feeding it forward, until the forward face 37 of the clutch 26 strikes the top 14 of the plug 5, whereupon the weight 22 urges the clutch operating member 27 forward until the ring portion 29 rides over the taper 30 sufficiently far to permit the clutch 26 to release.

The clutch members 26 are spring members which tend to spring away from the lead 7 at their forward end, and this spreading movement is limited by the ring 29 which surrounds the forward end portion 38 of the clutch 26, the periphery of the forward end portion 38 being preferably circular as indicated at 39 and fitting the bore of the ring 29. Between the rear end of the cylindrical peripheral portion 39 and the taper 30 may be provided a short taper 40 having a greater rate of taper than the taper 30 so that the inside corner 41 of the ring 29 will catch the steep taper 40 to insure that when the spring 31 moves the parts from the position shown in Figs. 2 and 3 to the position shown in Fig. 1, the clutch operating member 27 and the clutch tube 24 will move as a unit rearwardly, with clutch 26 open, until the rear end 42 of the tube 24 strikes the guide block 12, whereupon the spring 31 continues to urge the clutch operating member 27 rearwardly so that ring 29 rides on taper 30 and then locks the clutch 26 on the lead 7.

The parts are now restored substantially to the position shown in Fig. 1 ready for another feeding movement if desired.

It will be apparent therefore, that while grasping the pencil 1 in the usual writing position in the hand, but elevated, by simply a wrist movement and while maintaining the writing grasp on the pencil 1, the lead 7 may be fed forward one or more times as desired.

10 In the modification shown in Figs. 5 to 8, no spring is employed. The pencil 50 shown in these figures may be operated in somewhat the same way as described above, the case 51 having a chamber 52 in which slides a weight 53 similar to weight 22, except that the forward end of weight 53 has an internal taper 54 to serve as an operating member for the clutch members 55 which tend to spring outwardly at their forward ends, but are locked to the lead 56 when the weight 53 is moved downwardly by its momentum due to a sudden movement of the wrist when the pencil 50 is held by the usual writing grasp. Rearward movement of the lead 56 is prevented, while forward feeding movement is permitted, by providing a clutch 57 in the tip or plug 58, the clutch 57 having a rearwardly facing taper 59 which fits in a forwardly facing taper 60 in the rear portion of the tip 58. The forward end of clutch 57 carries spring fingers 67 which fit around the lead 56. The clutch members 55 are carried at the forward end of a tube 61 which has a central bore 62 slightly larger than the lead 56. The rear end of tube 61 is secured for example by screw threads 63 to a guide sleeve 64 which slidingly fits inside of the bore 52. The guide sleeve 64 is arrested in its rearward motion by the guide block 65. The weight 53 is moved both forwardly and rearwardly by the wrist movement of the user and in its upper limit of movement shown in Fig. 6, the sleeve 64 abuts the guide block 65, the clutch 55 being open and a slight distance above the top 66 of the tip 58. When the wrist movement causes the pencil 50 to move forwardly and then stop, the forward movement of weight 53 first closes the clutch 55 to lock the same on the lead 56, the clutch 55 and lead 56 then moving forward under action of the weight 53, until clutch 55 strikes top 66 of the tip 58 as shown in Fig. 5.

50 As described in connection with Figs. 1 to 4, pencil 50 has a recess 68 for an eraser, a guide block 69 having a tapered feed hole 70 and a compartment 71 for lead sections which find their way through tapered hole 72 in the guide block 65.

In the modification shown in Figs. 9 to 12, inclusive, the pencil 80 is provided with a tip 81 having a spring and clutch barrel 82 in which is arranged a compression spring 83 acting on the clutch members 84 which have a slight rearwardly facing taper 85 fitting in the forwardly facing taper 86 inside of a ring 87 in the rear end of the tip 81. The clutch 84 permits forward feed of the lead 88 and prevents rearward movement thereof as in Figs. 5 to 8.

70 Fitting inside of the front end of the case 89 is a shell 90 having at its forward end an external annular ridge 91 fitting in a recess 92 adjacent the end of the case 89 and clamped therein and to the top 94 of the tip 81 by the case 89 in being secured to the tip 81 by screw threads 93. The rear end of shell 90 has an internal flange 95, the front side of which serves as a stop for a shoulder 96 on the clutch member 97 which has a cylindrical periphery fitting

loosely inside of the shell 90 and an outwardly facing internal slight taper 98 fitting the external taper 99 on the clutch members 100 which tend to spring outwardly and which project forwardly from a tube 101 having a bore 102 in which the lead 88 loosely fits. The rear end of tube 101 is screw-threaded as shown at 103 into the front end of the tubular weight 104, which has an axial bore 105 aligned with the bore 102 and in which the lead 88 is arranged. The front end of the weight 104 is reduced in diameter as indicated at 106 to accommodate a compression spring 107, the upper end of which bears against a shoulder 108 on the weight 104. The lower end of spring 107 bears on the rear face of flange 95. The clutch member 97 has a rearwardly projecting hollow stem 109 having an axial bore in which the tube 101 slidably fits.

As described in connection with the other modifications, pencil 80 has a recess 110 for an eraser, a guide block 111 having a tapered feed hole 112, and a storage chamber 113 for sections of lead which find their way through tapered hole 114 in the guide block 115. In this case, the weight 104 is also provided at its rear end with a tapered bore 116 to guide the lead 88 into the bore 105.

When the pencil 80 is thrust bodily forward and then checked or stopped, the weight 104 due to its momentum, continues its forward movement against the compression of spring 107, and in so doing feeds the lead 88 forward as the clutch members 97 and 99 ride forward together until the clutch member 97 strikes the top 94 of the tip 81, whereupon the clutch 99 in continuing its forward movement moves forwardly with respect to the clutch member 97 thereby releasing the grip on the lead 88, the forward movement of clutch 99 terminating when it strikes the top 94 of the tip 81. Thereupon the spring 107 moves the weight 104 rearwardly as well as clutch 99 which is fastened to weight 104, and the clutch 99 in springing out and the taper of this clutch being slight, and clutch member 97 being light in weight, the clutch 99 carries with it the clutch member 97 from the position shown in Fig. 10, until the shoulder 96 comes to rest against the flange 95, and thereafter the weight 104 continues its rearward movement to close the clutch 99 and grip the lead 88, whereupon the pencil 80 is ready for the next feeding movement of the lead 88.

In the preferred form shown in Fig. 13, the pencil 120 is provided with a tip 121 having a bore 122 in which slidably fits the clutch member 123. The forward end of recess 122 has a wall 124 which serves as a stop for the clutch 123 and for the spring clutch members 125. The tip 121 has a ring 126 which carries spring friction members 127 which fit around the lead 128. The bore 122 extends into the bore 129 of a sleeve 130 having an inwardly projecting flange 131 the front face of which provides a shoulder 132 to serve as a stop for the shoulder 133 on the clutch 123. The sleeve 130 has external screw threads 134 which fit the internal threads 135 on a rearwardly projecting ring 136 on the tip 121. The ring 136 has external screw threads 137 fitting the internal screw threads 138 on the inside of the front end of the case 119. The clutch members 125 normally tend to spring outwardly, as previously described, and they project forwardly from a sleeve 139 having a bore 140 in which the lead 128 slides. The sleeve 139 at its rear end is screw threaded into the weight 141 as indicated at 142. Weight 141 has a central bore 143

in which the lead 128 slides, and this weight slides in a weight compartment 144 formed by the bore of the case 139. Weight 141 and its connected parts are urged rearwardly by a compression spring 145, the rear end of which bears against the end of weight 141 as indicated at 146 and the front end of which bears against flange 131. The clutch member 123 has a rearwardly projecting shell 147 which slidably fits on the outside of sleeve 139.

The operation of the preferred form shown in Fig. 13 is substantially the same as that of the other modifications, generally speaking. When the pencil 120 is thrust forward and then stopped, weight 141 continues its forward movement against the action of spring 145, feeding forward the lead 128 as the clutch members 123 and 125 are locked to the lead 128, at this time and as shown in Fig. 13. This forward feeding movement continues until the front end 148 of the clutch 123 comes to rest at the wall 124, whereupon the weight 141 continues its forward movement and carries with it the clutch members 125 which unlock from the lead 128. The forward movement of weight 141 is limited by clutch members 125 striking the wall 124 or the ring 126. Thereupon the spring 145 returns the weight 141 rearwardly and this weight in being attached to the clutch members 125 of course carries them rearwardly and clutch 125 due to springing out, and also due to the slight taper 149, between the exterior of clutch 125 and the interior of clutch 123 and also due to the lightness in weight of the clutch 123, the clutch 125 carries the clutch 123 rearwardly with it, as in Figs. 9 to 12, until the clutch 123 comes to rest against the flange 131. Thereafter, the weight 141 and clutch 125 continue their rearward movement due to the action of spring 145, and thereby the taper 145 closes the clutch 125 and grips it to the lead 128. The pencil 120 is then ready for the next feeding movement of lead 128 when and as desired.

One advantage of the pencil shown in Fig. 13 is that all of the operating parts of the feeding mechanism are mounted as a unit with the tip 121, whereby such units are readily interchangeable and each thereof may be readily inserted into and removed from the case 119 of the pencil 120.

As described in connection with the other modifications, pencil 120 has a storage chamber 150 for sections of lead which find their way through the tapered bore 121 in the guide block 152, and an eraser recess as shown in other figures.

It will be apparent that various other modifications may be made in the invention without departing from the spirit of the following claims, and that in all cases material other than brass may be employed for the weight. Also, any suitable material such as metal or otherwise may be used for the other working parts of the various modifications shown, except, perhaps, for the springs which of course are usually of metal.

I claim:

1. A pencil having a case, a weight movable in said case by bodily movement of said case, and a reciprocating feed chuck for the lead operated by relative movement of said weight and said case.

2. A pencil having a case, said case having a weight compartment, a weight movable in said compartment by bodily movement of the pencil without changing the writing grasp on the pencil,

and a reciprocating feed chuck for the lead controlled by movement of said weight.

3. A pencil having a case, a weight in said case movable relatively to said case in one direction, solely by the momentum of said weight, spring means for moving said weight in the opposite direction, and a reciprocating feed chuck having an axially bore for the lead operated by relative movement between said case and said weight.

4. Means for feeding the lead in a lead pencil without changing the writing grasp on the pencil, said means comprising a weight slideable in the pencil, stops defining a path of fixed length for the movement of said weight and means for translating momentum of said weight, due to a checked movement of the pencil, into feeding movement of the lead.

5. A pencil comprising a case having therein a weight movable by its momentum and recipro-

cating over a path of fixed length, and a lead feeding chuck controlled by movement of said weight.

6. A pencil having a case, a weight movable in said case by bodily movement of said case, and lead feeding means operated by relative movement of said weight and said case, said weight and said lead feeding means having aligned bores therethrough for the lead.

10 7. A pencil having a case, said case having a lead storage chamber and a point, a weight movable in said case between said storage chamber and said point, said weight being movable by bodily movement of said case, and lead feeding means for feeding the lead from said storage chamber to said point, said lead feeding means being operable by relative movement of said weight and said case.

J. D. BUCHANAN.
